J. H. PIERCE

MARINE PROPULSION DEVICE

Filed Oct. 10, 1924

INVENTOR.

James H. Pierce.

BY

Frank C. Larman.

ATTORNEY.

UNITED STATES PATENT OFFICE.

JAMES H. PIERCE, OF BAY CITY, MICHIGAN.

MARINE PROPULSION DEVICE.

Application filed October 10, 1924. Serial No. 742,814.

REISSUED

To all whom it may concern:

Be it known that I, JAMES H. PIERCE, a citizen of the United States of America, and a resident of Bay City, in the county of Bay 5 and State of Michigan, have invented new and useful Improvements in Marine Propulsion Devices, of which the following is a specification.

This invention relates to improvements 10 in marine propulsion devices, and particularly to the submerged gear case and propeller shaft housing assembly of the conventional outboard motor.

One object of the invention is to design 15 a propeller shaft housing and gear case assembly having new and novel means for forcing the water to the water jacket of the motor and whereby the usual pump is eliminated.

Another object is to design power and 20 propeller shaft housings of simple and substantial design, and in which water intake and overflow passages are cored in or piped to the water jacket of the motor.

A further object is to design a gear casing 25 to eliminate the possibility of sand or water getting into the gears or propeller shaft bearings.

The above and other objects will appear 30 as the specification progresses, reference being had to the accompanying drawing in which I have shown the preferred embodiment of my invention, and in which like reference numerals indicate like parts 35 throughout the several views thereof.

In the drawing.

Fig. 1 is a fragmentary vertical sectional view of a power shaft housing gear case and propeller shaft housing.

Fig. 2 is a section taken on the line 2—2 of Fig. 1.

Fig. 3 is a front view thereof.

Fig. 4 is also a sectional view similar to that shown in Fig. 2 showing an alternate 45 form of construction.

It has always been somewhat troublesome in outboard motors to provide simple means for forcing water up to cool the cylinders of portable motors of this type, as it 50 generally necessitates a force pump equipped with valves operated by a cam or other device, and these valves stick and grind due to the sand and foreign matter taken into the pump with the water, the pump is therefore short lived, expensive to build, and is 55 subject to clogging, it also necessitates a

bulky design which must be forced through the water, with the consequent loss of power, and these objectionable features I have overcome by eliminating the pump and providing a structure not affected by sand and foreign matter and which has no movable parts.

In my improved design I provide a vertically extending power shaft housing which 60 can be cast of aluminum or other light metal, this is preferably wedge shaped as shown, the edges being thin and sharp to eliminate water resistance.

A power shaft 3 is rotatably mounted in 70 this power shaft housing which is cored to receive it, and a bushing 4 is fitted to the lower end thereof which is cored to form a gear casing, a thrust bearing 5 being mounted in this bushing, and a bevel gear 75 6 is keyed on the lower end of the power shaft, meshing with and driving a bevel gear 7 mounted on a propeller shaft 8, which is journaled in a propeller shaft housing 9, this housing is cylindrical in shape, 80 the top half being cast integral with the power shaft housing, the lower half being machined and fitted thereto, and is held in place by screws (not shown) in the usual manner. Bearings 10 and 11 are mounted 85 in this housing, and the propeller shaft 8 is journaled thereon, the one end projecting beyond the housing and having a propeller member 12 fixed thereon, the front end of the shaft being journaled in a sleeve bearing 90 13 formed in the housing proper. It will also be obvious that the front end or nose of the housing can be formed separate and threaded to engage the main body, or it 95 can be bolted thereto if desired, this is how- ever merely a detail of construction.

An intake port or opening 14 is located in the end or nose of the propeller shaft housing, and leads to a chamber 15 through which the propeller shaft extends, said 100 chamber communicating with an upwardly extending passage 16 formed in the power shaft housing. A spiral 17 formed of thin metal, is mounted on the propeller shaft 8 in this chamber 15, and as the water enters 105 through said port, the spiral forces it up this passage and to the water jacket of the engine, (not shown).

A similar passage 18 is formed on the opposite side of the power shaft for accom- 110 modating the overflow or discharge, and opens directly adjacent the propeller and

- below the water line, locating the overflow at this point also has its advantages, as the displacement of water by the propeller sets up a partial vacuum to accelerate the circulation or flow of the water in the water jacket, further, when reversing with a motor where a conventional pump is used, the supply is either entirely cut off, or reduced to such extent as to be entirely insufficient.
- 10 In my improved construction a full supply is assured regardless of the direction of rotation of the motor, as the reversing thereof merely reverses the direction of flow of water to the water jacket, the propeller forcing it into the passage 18, the spiral 15 forcing it out of the intake port above described.
- In Fig. 4 of the drawing I have shown an alternate form of construction, the power 20 shaft housing being pressed, with tubes of brass or copper secured therein for the propeller shaft and water passages, this makes a very light and economical housing, the principle being identically similar to that 25 above described. It will also be obvious that a screen should be placed over the intake port to exclude chips, weeds and foreign matter.
- From the foregoing description it will 30 be obvious that I have perfected a very simple, substantial and economical marine propulsion device which is very efficient in operation, and is composed of a minimum number of parts.
- 35 What I claim is:—
1. In a marine propulsion device provided with a vertically disposed knife edged wedge shaped power shaft housing, a propeller shaft housing, a power shaft in said power shaft housing, water intake and outlet passages adjacent the power shaft, and an intake port in the propeller shaft housing and communicating with said intake passage.
  2. In a marine propulsion device provided with a vertically disposed power shaft housing, a longitudinally disposed propeller shaft housing integral therewith, water intake and outlet passages in said power shaft housing, an intake port in the propeller shaft housing and communicating with the intake passage, and a spiral interposed between said port and said passage for forcing water up said intake passage.
  3. In a marine propulsion device formed with a vertically disposed power shaft housing, a longitudinally disposed propeller shaft housing integral therewith, a propeller journaled thereon, water intake and outlet passages in said housing, an outlet port opening directly adjacent the propeller, an intake port in the propeller shaft housing and communicating with the intake passage, and means mounted in the said housing for forcing water up the intake passage.
  4. In a marine propulsion device provided with a power shaft housing, a propeller shaft housing formed integral therewith, intake and outlet passages in said power shaft housing, an intake port in the propeller shaft housing and communicating with the said intake passage, and a spiral interposed between said port and said passage.
  5. In a marine propulsion device provided with a power shaft housing, a propeller shaft housing integral therewith, intake and outlet passages formed in said power shaft housing, an intake port in said propeller shaft housing and communicating with said intake passage, and a spiral interposed between said port and said passage for forcing water into said passage.
  6. In a marine propulsion device provided with a vertically disposed wedge shaped power shaft housing having sharp edges, a gear casing on the lower end thereof, a propeller shaft housing, water intake and outlet passages adjacent the power shaft and below the normal water line, and an intake port in the propeller shaft housing and communicating with said intake passage.
  7. In a marine propulsion device provided with a power shaft housing, intake and outlet passages therein, a power shaft journaled therein, a propeller shaft housing below said power shaft housing, a propeller shaft therein, and having driving connection with said power shaft, an intake port in the propeller shaft housing and communicating with the intake passage, and a spiral mounted on the propeller shaft and interposed in said passage.
  8. In a marine propulsion device provided with a vertical power shaft housing, a propeller shaft housing integral therewith, intake and outlet passages in said housing, a power shaft journaled therein, and having driving connection with a propeller shaft journaled in the propeller shaft housing, a propeller mounted thereon, a spiral mounted on said shaft in the said housing, an intake port communicating with said intake passage, and a discharge port directly adjacent the propeller.
  9. In a marine propulsion device provided with a vertically disposed power shaft housing, a longitudinally disposed propeller shaft housing formed integral therewith, intake and outlet passages formed in said housing and forming a continuous circuit with the water jacket of a motor, an intake port in the nose of the propeller shaft housing and communicating with the intake passage, and an outlet port in the power shaft housing directly adjacent the propeller.
  10. In a marine propulsion device provided with a power shaft housing, a propeller shaft housing integral therewith, a propeller shaft journaled therein, intake and

outlet passages in said housing and forming a continuous circuit with the water jacket of a motor, an intake port in the propeller shaft housing, and a spiral mounted on the propeller shaft and interposed in said intake passage.

11. In a marine propulsion device provided with a power shaft having driving connection with a propeller shaft journaled in a propeller shaft housing, intake and outlet passages adjacent said power shaft, an intake port in said gear casing and connecting with said intake passage, and a

spiral mounted on the propeller shaft and interposed in said intake passage. 15

12. In a marine propulsion device formed with a vertically disposed knife edged symmetrical wedge shaped power shaft housing a propeller shaft housing formed integral therewith, and intake and discharge 20 passages in said propeller shaft and power shaft housings opening below the normal water level.

In testimony whereof I affix my signature.

JAMES H. PIERCE.
